UNITED STATES PATENT OFFICE.

HENRY E. HAWKINS, OF CLOVIS, CALIFORNIA.

COMBINED BLOTTER-HOLDER AND RULER.

1,059,154.

Specification of Letters Patent. Patented Apr. 15, 1913.

Application filed October 7, 1911. Serial No. 653,297.

To all whom it may concern:

Be it known that I, HENRY E. HAWKINS, a naturalized citizen of the United States, residing at Clovis, in the county of Fresno, 5 and State of California, have invented new and useful Improvements in Combined Blotter-Holders and Rulers, of which the following is a specification.

An object of the invention is to provide 10 a combined blotter holder and ruler, the blotters being removable from the holder for the purpose of replacing the same by new ones.

For the purpose mentioned, use is made 15 of an integral piece of flexible material bent to form a longitudinally extending slot adapted to slidably receive a blotter, an end of the said piece of material being slightly bent to retain the blotter in the slot, the 20 other end of the said piece of material being bent at an angle to form a straight edge.

Reference is to be had to the accompanying drawings constituting a part of this 25 specification, in which similar characters of reference denote corresponding parts in all the views, and in which—

Figure 1 is a perspective view of my device. Fig. 2 is an enlarged vertical sectional view taken substantially on the line 2—2 in 30 Fig. 1.

Referring more particularly to the views, I provide a flexible piece of material 10 having a portion 11 thereof bent upon itself 35 to form a side 12, thus forming a slot 13 between the portions 11 and 12, an end 14 of the said piece of material being slightly bent toward the portion 12 to restrict the opening of the slot. The portion 12 is then 40 bent upon itself to form an upper side 15 having the end 16 thereof slightly bent and forming a straight edge 17.

In the use of my device, a blotter 18 is attached to the holder by sliding one of the longitudinal ends of the blotter into the slot 13 from one end thereof. Thus, it will be 45 seen that the bent edge 14 will prevent the blotter from being pulled directly out of the slot 13 and will act as a means for properly retaining the blotter in engagement with the holder. 50

Suitable graduations 19 can be made on the upper side 15 and by bending the end 16, the straight edge 17 can be used as a means for cutting paper and the like, aside from performing the function of a scale or 55 ruler.

Although the device described herein can be made from flexible metals, such as aluminum or the like, I intend to preferably manufacture the holder of celluloid or rubber, it being understood, however, that I do not limit myself to the grade or kind of material employed in the construction of the holder. 60

I claim:—

As a new article of manufacture, a combined blotter and ruler comprising a single piece of material bent longitudinally to provide three substantially parallel superimposed strips, one of the outermost strips 70 having its free edge extending beyond and bent downwardly toward the other two strips to form a straight edge, and a blotter 75 for removable insertion between the other two strips.

In testimony whereof I affix my signature in presence of two witnesses.

HENRY E. HAWKINS.

Witnesses:

F. M. HARBERT,
W. H. SOWELL.
